(57) **CLAIM**

The ornamental design for a slope level, as shown and described.

DESCRIPTION

FIG. 1 is a perspective view of a slope level showing my new design;

FIG. 2 is a front elevational view showing the design for the slope level of FIG. 1;

FIG. 3 is rear elevational view showing the design for the slope level of FIG. 1;

FIG. 4 is a left side elevational view showing the design for the slope level of FIG. 1;

FIG. 5 is a right side elevational view showing the design for the slope level of FIG. 1;

FIG. 6 is a top elevational view showing the design for the slope level of FIG. 1; and,

FIG. 7 is a bottom elevational view showing the design for the slope level of FIG. 1.

The broken line showing of portions of the slope level is included for illustrative purposes only and forms no part of the claimed design.
